US00D959227S

(12) **United States Design Patent** (10) **Patent No.:** **US D959,227 S**
(45) **Date of Patent:** **** Aug. 2, 2022**

(54) **TOOL HOLDER ASSEMBLY**

(71) Applicant: **Cricut, inc.**, South Jordan, UT (US)

(72) Inventors: **Steven Bandis**, West Jordan, UT (US);
Jeremy Burton Crystal, Springville,
UT (US)

(73) Assignee: **Cricut, Inc.**, South Jordan, UT (US)

(**) Term: **15 Years**

(21) Appl. No.: **29/771,267**

(22) Filed: **Feb. 22, 2021**

Related U.S. Application Data

(60) Division of application No. 29/689,742, filed on May 1, 2019, which is a continuation of application No. PCT/US2018/044371, filed on Jul. 30, 2018.

(57) **CLAIM**

The ornamental design for a tool holder assembly, as shown and described.

DESCRIPTION

FIG. 1 is a front, right, top isometric view of the claimed design.

FIG. 2 is a front, right, bottom isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top view thereof; and,

FIG. 8 is a bottom view thereof.

Broken lines in the drawing views form no part of the claimed design. The shade lines in the drawing views show contour and not surface ornamentation of the claimed design.

1 Claim, 7 Drawing Sheets
